UNITED STATES PATENT OFFICE.

WILLIAM G. ALGEO, OF ROCHESTER, PENNSYLVANIA.

DESIGN FOR COFFIN-TOP.

Specification forming part of Design No. 5,314, dated October 17, 1871.

To all whom it may concern:

Be it known that I, WILLIAM G. ALGEO, of Rochester, in the county of Beaver and State of Pennsylvania, have invented a new and useful Design for Coffin-Tops; and I do hereby declare the following to be a full, clear, and exact description thereof, reference being had to the accompanying drawing forming part of this specification, in which—

Figure 1 is a view of a coffin-lid having a plain top, and Fig. 2 is a view of a coffin-lid having a raised or ornamental top.

Like letters of reference indicate like parts in each.

My improved design relates to the conformation of the upper outer edge of the lid or cover of the coffin or casket, whether such lid be flat, as in Fig. 1, or raised, as in Fig. 2; and it consists in a series of moldings terminating at suitable intervals in a plain finish, of sufficient length for the insertion of screws, the attachment of escutcheons, or other ornamentation.

The outer edge of the lid or cover A conforms in shape to that of the body of the coffin or casket. The ends B are made of any desired shape. The upper outer edge of the rim, lid, or cover A is molded at suitable intervals in any desired style, between the parts C, which are left unmolded, or with a plain finish, and through which the fastening-screws are to be inserted, and on which escutcheons or other ornamentations may be placed.

What I claim as my improved design for coffins and caskets is—

The lid or cover having in its upper outer edge moldings alternating with a plain finish, as described and shown.

In testimony whereof I, the said WILLIAM G. ALGEO, have hereunto set my hand.

WM. G. ALGEO.
